UNITED STATES PATENT OFFICE.

EDWARD FAVRE PERRET, OF LOCLE, SWITZERLAND.

IMPROVEMENT IN WATCHES.

Specification forming part of Letters Patent No. 40,358, dated October 20, 1863.

To all whom it may concern:

Be it known that I, EDWARD FAVRE PERRET, of Locle, Switzerland, have invented a new and useful Improvement in Watches; and I do hereby declare that the following is a full, and complete specification of the same, reference being had to the annexed drawings, forming a part hereof, which are fully described herein, and in which—

Similar letters indicate similar parts in all the figures.

My invention is an improvement in the manner of connecting the "seconds-hand" with the train, whereby I am enabled to start and to stop that hand at pleasure without affecting the train, and it is particularly applicable to watches having a central, or, as it is called, an "independent" seconds-hand.

In the drawings, Figure I represents a plan view of the plate under the dial, so much only of the parts being shown as is necessary to explain my invention. Fig. II is a vertical central section; and Fig. III is a plan view of the under side of the plate, and of the parts of my improvement.

At *a* is seen the fourth or "seconds" wheel of the train, *a'* being its pinion. This wheel and its pinion are free to revolve around the staff *b* of the seconds-hand, which has its pivot in the outer back plate of the watch, and extends through a tube on the central plate to the dial in the usual manner, and seen at *c*.

To cause the seconds-wheel to give rotation to the staff *b*, there is a collet or clutch, *d*, made to slide upon the staff and also to turn with it. There is a coiled spring, *e*, on the staff, tending to keep the clutch pressed against the end of the pinion *a'* of the seconds-wheel, and when so pressed the friction of the two is sufficient to insure a proper rotation of the seconds-hand. When the seconds hand is to be stopped, the clutch is to be lifted away from the end of the pinion, and to be held so firmly as to prevent the friction of the pinion around the staff from carrying the staff with it. This is effected by a forked lever, *f*, which embraces the clutch, as shown in Figs. II and III, and which, when holding the clutch away from the pinion, compresses the coiled spring *e*, thereby making the friction of the clutch against the forks of the lever sufficient to hold the staff at rest. The lever *f* has its fulcrum at *i*; thence it passes through to the upper side of the central plate, as seen in Fig. II, where its other end is made to ex-

tend partially over the face of a ratchet-wheel, *k*, on the plate. This wheel has two sets of ratchet-teeth, the one, *l*, upon its edge, and these must be an even number, the other set, *n*, is upon the face of the wheel, near its edge, and of half the number of the set *l*. Both sets of teeth are inclined in the same direction, and the outer end of the lever *f* is made to press down always upon the teeth *n* by the spring *o*. A pawl, *p*, is so placed with regard to the ratchet-wheel that it shall take into the teeth *l* on the edge, and be operated by means of a stud, *r*, which extends out through the case, to be depressed by the finger. It has also a sprung, *s*, which serves the double purpose of keeping the pawl engaged with the ratchet, and of retiring it outward for the next depression.

The operation will be as follows: If, at commencing, the outer arm of the lever *f* be resting in the bottom of one of the teeth *n*, as shown in the several figures, the clutch *d* will then rest against the end of the pinion *a'* of the seconds-wheel, and will cause the staff of the seconds-hand to be carried around with it. If, now, the stud *r* be pressed in, the ratchet-wheel will be carried onward one notch of the outer teeth, *l*, and as there are twice as many of these as of the teeth *n* the lever-arm *f* will ride up one of those and remain held up. This action withdraws the clutch *d* from the end of the pinion, and also holds the staff, as before explained. The seconds hand is now stopped, although it is obvious that the other movements will still progress. If the stud be now pressed in again, the arm of the lever will drop over the tooth upon which it was held up, and the clutch will again press upon the end of the pinion.

It will be seen that by my improvement only a single mainspring and train are required to obtain all the advantages of an independent seconds-hand for the measurement of fractions of a minute.

I claim—

So combining the seconds-hand with the fourth or seconds wheel that the seconds-hand can be stopped, and permanently held or started at pleasure without affecting the movements of the seconds-wheel, substantially as set forth.

In witness whereof I have hereunto subscribed my name.
